(57) **CLAIM**

The ornamental design for an ornamental cover for liquid container, as shown and described.

DESCRIPTION

FIG. 1 is a front perspective view of an ornamental cover for liquid container, shown in condition of use;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.

The broken lines illustrate portions of the cover and environmental structure which form no part of the claimed design.
